A. R. SELDEN

LOOSE LEAF BINDER

Filed Oct. 31, 1921

INVENTOR.
Arthur R. Selden
by James T. Simons
his attorney

UNITED STATES PATENT OFFICE.

ARTHUR R. SELDEN, OF ROCHESTER, NEW YORK.

LOOSE-LEAF BINDER.

Application filed October 31, 1921. Serial No. 511,864.

To all whom it may concern:

Be it known that I, ARTHUR R. SELDEN, a citizen of the United States, and resident of Rochester, in the county of Monroe and State of New York, have invented certain new and useful Improvements in Loose-Leaf Binders, of which the following is a specification.

The present invention relates to loose leaf binders and more particularly to the type employing impaling projections passing through the sheets or leaves to be held. An object of this invention is to provide an impaling projection which may readily be made of different lengths. Another object of this invention is to provide an impaling projection formed of two sections connected by screw threads, one of which is rigidly connected to a binding member and the other of which turns on the rigidly secured one. Still another object of the invention is to provide an adjustable impaling projection which will maintain its effective condition of uniform diameter, so that for any extension its diameter throughout will correspond with the openings in the leaves. A further object of the invention is to so house the operative parts that they will not be visible, while yet maintaining a compact structure.

To these and other ends the invention consists of certain parts and combinations of parts, all of which will be hereinafter described, the novel features being pointed out in the appended claims.

In the drawings:

Fig. 1 is a plan view of the rear end of the binder with one half shown in section on the line 1—1, Fig. 2;

Fig. 2 shows in elevation the rear end of the binder with one half shown in section on the line 2—2, Fig. 1;

Fig. 3 is a sectional view through the rear edge of the binder on the line 3—3, Fig. 2;

Fig. 4 is a sectional view of one of the impaling pins in the direction of its length;

Fig. 5 is a detail view showing the manner in which the impaling pins are adjustable; and

Fig. 6 shows one of the impaling pins in elevation.

In the illustrated embodiment of the invention the binder comprises two members each formed of a cover 1 connected by a flexible or hinging portion 2 with a binding

member. Each binding member, in this instance, embodies a flat tube or hollow member 3 and two impaling pins or posts, the impaling posts preferably being supported from tubular inserts 3^a fitting in the tube 3.

In this instance, each impaling projection is composed of an end member 4 having a screw-threaded projection 5, one or more intermediate members 6, each having a screw-threaded socket 7 for receiving the screw-threaded projection 5 and having a screw-threaded projection 8 for interlocking with another section. In addition to one or more intermediate sections 6, the post may embody a section 9 which, in this instance, is of tubular formation and has threaded portions 10 and 11 respectively, one for engaging a threaded projection on another section and the other for engaging a threaded section 12 which projects from an inner wall of the hollow member 3^a through an opening 13 in the opposite wall. It is apparent that with this invention the impaling pins or posts may be made of different lengths by adding or eliminating sections 6, and it is also apparent that the length may be varied by adjusting the section 9 on the threaded section or projection 12.

With the end in view of holding the section 9 in different adjusted positions on the screw threaded section 12, the section 9 may be provided with a longitudinally extending groove or slot 14 and a locking device may be provided preferably within the tube 3. In this instance, this locking device is in the form of a lever 15 pivoted at 16 to the insert 3^a and having a nose 17 adapted to enter the slot 14, as shown in Figs. 1, 4 and 5. A spring 18 acts on this lever normally to hold the latter toward locking position. One end of the lever extends into slots 19 formed in the tube 3 and insert 3^a so that such lever may be pressed out of locking position against the action of its spring 18. A series of indications or marks 20 may be provided on the member 9 to indicate the adjustment of the impaling pin or post.

The posts on one of the binding members are situated nearer together than those on the other binding member, and these two posts operate through openings 21 in the leaves 22. The posts which are farther removed operate through openings 23 in the leaves. This arrangement permits both of

the binding members to support the leaves in proper relation for cooperation with the impaling posts or projections of the other member.

5 For the purpose of locking the binding members together means is provided on one of the binding members for cooperation with the impaling posts or projections of the other binding member. In this instance, two 10 locking devices are provided on the binding member that carries the posts passing through the openings 21 of the leaves. These locking devices, in this instance, each embody a lever 24 mounted to turn on a pin 25, which is supported by two ears 26 struck up from the insert tube 3^a. This lever has one end 27 formed with an opening adapted to receive one of the impaling pins or posts, in order that the walls of the openings may 15 20 clutch or grip the post to prevent the latter being withdrawn from the binding member carrying the locking device. A spring 28 acts on this clutch lever to hold it in clutching position. The clutch lever also has an end 29 disposed adjacent aligned openings 30 in the tubes 3^a and 3 so that pressure may be received from a finger passed through such openings. In order to release the binder, both of the clutch levers must be operated 25 30 simultaneously and this permits the two binding members to be separated. The cloth 31, which covers the binding members except at their ends which are closed by caps 31^a also covers the openings 19 and 30, 35 so that while the levers 15 and 25 may be operated from the exterior of the binding members, the operating ends of such levers are invisible.

40 The impaling posts or projections are made of lengths to correspond to the number of leaves held between the binding members, this result being secured by eliminating the sections 6 of the post or by adding as 45 many of such sections as desired and, at the same time, adjusting the sections 9 on the screw section 12. Owing to the fact that the screw-threaded inner sections of the impaling posts project from the inner walls of 50 the hollow binding members through openings in opposite walls, the posts for any adjustment maintain a uniform diameter throughout their effective lengths and correspond with the diameter of the openings in the leaves. The two binding members are

fitted together and the locking clutches automatically slide over the posts or projections which pass through the openings 23 in the leaves, and establish a clutching relation with said posts or projections and prevent the separation of the binding member until the finger portions 29 of the clutching members are depressed when the posts are freed and the binding members may be separated.

55 60 65 What I claim as my invention and desire to secure by Letters Patent is:

1. A loose leaf binder embodying an impaling post or projection comprising two sections one of which has a screw-thread engagement with the other to effect the adjustment of such post or projection and is 70 provided with a longitudinally extending notch, and a locking device cooperating with the walls of the notch to hold the section against turning.

75 80 85 90 95 2. A loose leaf binder embodying an impaling post or projection comprising two sections one of which has a screw-thread engagement with the other to effect the adjustment of such post or projection and is provided with a longitudinally extending notch, and a locking device cooperating with the walls of the notch to hold the section against turning, a spring acting on said locking device to maintain it normally toward locking position.

3. A loose leaf binder comprising a tubular binding member having an opening in one wall, an impaling pin or projection embodying two sections one of which is in the form of a screw-threaded projection extending from an inner wall of the tubular binding member through the opening and the other of which turns in said opening on said screw-threaded projection, a locking device for said second-mentioned section arranged within said tubular binding member and having a portion operable from the exterior of said binding member.

100 105 110 115 4. A loose leaf binder comprising a hollow binding member provided with an opening in one wall, an externally threaded post section secured to an inner wall of said binding member, and extending through said opening, and an internally threaded post section adjustable in said opening on the first-named post section.

ARTHUR R. SELDEN.
